UNITED STATES PATENT OFFICE.

ALFRED BOISAUBIN, OF BROOKLYN, NEW YORK.

TOBACCO-PIPE.

No. 824,971.

Specification of Letters Patent.

Patented July 3, 1906.

Application filed August 17, 1905. Serial No. 274,520.

To all whom it may concern:

Be it known that I, ALFRED BOISAUBIN, a citizen of the United States, residing at Brooklyn, in the county of Kings and State of New York, have invented certain new and useful Improvements in Tobacco-Pipes, of which the following is a specification.

My invention relates to tobacco-pipes and belongs directly to that class of pipes which is provided with an interior receptacle for holding the burning tobacco and a cover furnished with a tamping or presser device for pressing the tobacco down in the receptacle.

The object of my invention is the production of a tobacco-pipe of the general character stated having a particular construction and arrangement of parts and equipped with means for pressing the tobacco down in the pipe as used and also having a device arranged to stir up the tobacco from below in order to make the pipe draw well.

I accomplish the stated objects by fashioning and associating the parts substantially as illustrated in the accompanying drawings, of which—

Figure 1 represents a vertical section of the entire invention, showing all parts in their relative positions; and Fig. 2 is a top view. The stem is not shown in Fig. 2.

Like letters are used to refer to like parts throughout.

The letter A marks the bowl of the pipe, and B the stem.

The receptacle within the bowl in which the tobacco is placed is designated by letter C. It possesses perforations c. The bottom of receptacle C is extended downwardly into a nipple D, which is threaded exteriorly, and the nipple has a central passage or bore E.

The cover of the pipe is marked F. It has the perforations f to permit air to enter, and it engages or is seated in the mouth of the receptacle C, as plainly shown in Fig. 1. Vertically through the cover there passes movably a push-rod G, yieldingly supported in a raised position by the encircling helical spring H. It will be now understood that if the rod be pressed downwardly and the pressure removed it will rise under the reaction of the spring H.

At the foot of the push-rod G is secured the presser-plate J, having perforations j. The office of the plate and rod is to ram the tobacco down into the bowl in the usual manner when smoking in order that the contents may burn uniformly and not too rapidly.

To removably secure the cover F at the mouth of the receptacle C, I construct the cover with a peripheral groove K, and the inside of the receptacle is provided, near its upper edge, with a projecting pin L, adapted to engage the groove. When the cover is placed in position, it is turned to bring the recess M over the pin L, and the recess thus passes the pin into the groove K, and by turning the cover another portion of the groove is brought into engagement with the pin, and the cover can only be removed by again turning it reversely, as will be readily understood. I do not confine myself to this particular association of devices to secure the cover and may substitute any such equally well known for the purpose.

The letter N marks a screw-cap situated at the bottom of the bowl and engaging the threaded nipple D of the receptacle C, before referred to. Rising centrally in cap N is a rod O, and the top of the rod, which will be noted is situated within the receptacle C, is split into a number of fingers P. The office of the fingers is to stir up the tobacco as it is tamped down by the plate J, thereby preventing the formation of a mass too compact to draw well. By tamping with the finger of the right hand, in which hand the bowl may also be held, and by repeating the movements of slightly unscrewing and screwing up the cap N the tobacco may be at once tamped and stirred into satisfactory smoking condition. In order that the receptacle C may not be rotatively displaced when turning the cap N, it is held, as shown, by passing the tapering end b of stem B through an office in the side of the receptacle.

Having now described my invention and explained the mode of its operation, what I claim is—

1. In a tobacco-pipe, the combination with the bowl, of a receptacle arranged within the bowl and having perforations, said bowl and receptacle having corresponding holes through their sides, a pipe-stem inserted in said holes thereby preventing the said receptacle from rotating, and a stirring device constructed and arranged to project into said receptacle from below and provided with means adapted to secure the receptacle in the bowl, substantially as described.

2. In a tobacco-pipe, the combination with the bowl, of a receptacle arranged within the bowl and having perforations, and a stirring device constructed and arranged to

project into said receptacle and provided with means adapted to secure the receptacle in the bowl, substantially as described.

3. In a tobacco-pipe, the combination with a bowl, of a perforated receptacle arranged within the bowl and having a threaded nipple extending through and below the bowl, a screw-cap N adapted to engage the said nipple, the said cap having a central standing rod disposed to extend upwardly into the said receptacle and having its upper extremity split into fingers for stirring the tobacco, substantially as described.

4. In a tobacco-pipe, the combination with a bowl, of a perforated receptacle arranged within the bowl and having a thread-

ed nipple extending through and below the bowl, a pipe-cover, devices arranged to press upon the tobacco in the receptacle from above, and a screw-cap N adapted to engage 20 the said nipple, the said cap having a central standing rod disposed to extend upwardly into the said receptacle and having its upper extremity split into fingers for stirring the tobacco, substantially as described. 25

In testimony whereof I affix my signature in presence of two witnesses.

ALFRED BOISAUBIN.
